F. C. LA MAR AND P. J. HOPKINS.
RENEWABLE ELECTRIC FUSE.
APPLICATION FILED AUG. 16, 1918. RENEWED MAR. 10, 1921.

1,376,342.

Patented Apr. 26, 1921.

UNITED STATES PATENT OFFICE.

FRANK C. LA MAR AND PETER J. HOPKINS, OF PITTSBURGH, PENNSYLVANIA.

RENEWABLE ELECTRIC FUSE.

1,376,342.

Specification of Letters Patent. Patented Apr. 26, 1921.

Application filed August 16, 1918, Serial No. 250,173. Renewed March 10, 1921. Serial No. 451,330.

To all whom it may concern:

Be it known that we, FRANK C. LA MAR and PETER J. HOPKINS, citizens of the United States, residing at Pittsburgh, in the 5 county of Allegheny and State of Pennsylvania, have invented a certain new and useful Improvement in Renewable Electric Fuses, of which the following is a specification.

10 This invention relates to electric fuses of the renewable type, and the object of the invention is to provide a renewable or refillable fuse of simple, economical and efficient construction, and which is easily and 15 readily assembled, and as easily and readily disassembled when blown or the fuse element becomes disrupted by an excess or overload current, for the purpose of recharging or refilling the fuse with a new 20 fuse element.

The invention consists in the details of construction and combination of parts, all substantially as we will now proceed more particularly to set forth and finally claim.

25 In the accompanying drawings, illustrating the invention, in the several figures of which like parts are similarly designated, Figure 1 is a side elevation of the assembled fuse. Fig. 2 is a horizontal longitudinal 30 section thereof. Fig. 3 is a vertical longitudinal section, looking in the direction of the arrows Fig. 2, the fuse element and terminal blades being shown in elevation. Fig. 4 is a partly sectional and elevational 35 view of the casing and its attached ferrule. Fig. 5 is an end view of the assembled fuse of Fig. 1, and Fig. 6 is an end view of the casing shown in Fig. 4, looking in the direction of the arrow A.

40 As shown in the drawings, the fuse comprises a tubular shell or casing 1 of fiber, or any suitable substantially refractory and insulating material, having one of its ends slightly reduced, at 2, and provided with 45 diametrically opposite notches 3, and fitted upon this reduced end is a metal, preferably brass, ferrule 4, provided with diametrically opposite ears 5, and as herein shown these ears 5 are preferably formed 50 by cutting slits in the edges of the ferrule and bending the slotted portions inwardly, said ears entering the notches 3 in the end of the casing. Screws 6 are screwed into or otherwise fixed in the ears 5 and project 55 beyond the end of the casing to receive knurled nuts 7 for a purpose presently ap-

pearing. The other end of the casing 1 is provided with an end cap 8 closely fitted thereupon and having in its end wall a central elongated opening 9 for the passage of 60 the knife-blade or terminal to which the fuse element is connected, and openings 10 upon opposite sides of the opening 9 for a purpose presently to be described. The end cap 8 may be permanently fixed to the end 65 of the casing in any suitable manner, but as herein shown it is removably attached to the casing.

The fuse element 11 may be of any suitable or well known construction, but preferably one which is provided with one or more blow-out or readily fusible restricted portions 12 between its ends, the ends of said fuse element being electrically connected, as by bolts or screws 13 and nuts 14, or any 75 other suitable readily detachable fastenings, to knife-blades or terminals 15 and 16.

The knife-blade or terminal 15, is provided with a cross-bar 17 constructed of a thin, flat, straight piece of metal of less 80 width than the blade, passed through and snugly fitting an opening 18 therein, adjacent to its connection with the fuse element and brazed or otherwise rigidly and permanently fixed therein. Screws 19 are fixed in 85 the opposite ends of the cross-bar 17 and project outwardly beyond the end of the casing, and are adapted to receive knurled nuts 20 when the fuse is assembled, as hereinafter described.

90 The knife-blade or terminal 16 is also provided with a cross-bar 21 consisting of a thin, flat, straight piece of metal of less width than the blade, passed through and snugly fitting an opening 22 therein adjacent to its connection with the fuse element, and brazed or otherwise rigidly and permanently fixed in said opening, and provided near its opposite ends with openings 23, through which the screws 6 are adapted 95 to pass in assembling the fuse. Removably fitted upon this end of the shell or casing, is an end cap 24, having in its end wall a central elongated opening 25 for the passage of the knife-blade or terminal 16, and 100 openings 26 upon opposite sides of the opening 25, for the passage of the screws 6, which project beyond the end of the cap and are adapted to receive the knurled nuts 105 7, to lock the parts in place.

110 The end caps 8 and 24 may be additionally secured in place by set-screws 27 car-

ried by the casing or shell and engaging slots in the edges of the end caps.

In assembling the fuse, the fuse element 11 having been secured to the knife-blades 5 or terminals 15 and 16, and the cap 24 removed from the casing, the knife-blade 15 with its attached cross-bar is first passed into the ferrule end of the casing and properly positioned so that its cross-bar 17 will 10 pass between the inwardly projecting ears 5 of the ferrule, and the fuse element and blades are then moved inward and turned until the blade 15 alines with and passes through the elongated slot or opening 9 in the end cap 8, and the screws 19 carried by 15 the cross-bar 17 thereby brought into alignment with the openings 10 in the end cap 8, when by further inward movement of the fuse element and knife-blades, the knife-blade 15 and the screws 19 will be projected 20 through their respective openings, and at the same time the openings 23 in the cross-bar 21 carried by the knife-blade 16, will register with and pass over the screws 6 25 fixed to the ears 5 of the ferrule 4 and be projected beyond the said cross-bar. The end cap 24 may then be placed upon the knife-blade 16, by passing the blade through the opening in the end cap, and forced upon 30 the end of the casing, the holes 26 registering with and passing over the screws 6 which project beyond the end cap, and the nuts 7 then fitted upon the screws 6 and turned up to secure the parts in place. The 35 nuts 20 are then placed upon the projecting ends of the screws 19 at the opposite end of the fuse and turned up tight to firmly hold the parts in place at this end of the fuse.

When the fuse is blown or disrupted by 40 an excess or overload current, and it is desired to remove the damaged fuse element and replace it by a new one, it is only necessary to remove the nuts 7 and 20 at the opposite ends of the fuse, and remove the 45 end cap 24, when the knife-blades and the parts of the damaged fuse element may readily be removed from the casing, and a new fuse element affixed to the knife-blades or terminals, and the fuse reassembled as 50 hereinbefore described. Or, both the end caps 8 and 24 may be detached from the ends of the casing for removing the damaged parts of the fuse element.

Although the invention is herein illustrated as applied to a knife-blade type of fuse, we wish to be understood as not limiting the invention to this specific application thereof, as the construction is equally applicable to the ferrule type of fuse, as it 60 will be seen that it would only be necessary to omit the projecting blade portions of the

terminals or fuse element carrying parts to provide a fuse of the ferrule type.

It is also to be understood, that we do not limit the invention to the exact details of 65 construction herein shown and described, as the same may be changed in various particulars and still be within the scope of the appended claims.

What we claim is:

1. A renewable electric fuse, comprising a tubular casing of insulating material, having notches in one of its ends, a ferrule fitted upon the notched end thereof and provided with inwardly projecting ears 75 passing through said notches, screws fixed in said ears and projecting beyond the end of the casing, a fuse element and terminals to which it is connected for supporting the fuse element in the casing, said terminals 80 having cross-bars fixed therein, one of said cross-bars provided at its ends with openings adapted to engage the screws projecting from said ears, an end cap fitted upon the end of the casing over said ferrule and 85 provided with openings for the passage of said screws, nuts screwed upon the projecting ends of said screws for locking the parts in place, and means for securing the cross-bar of the other terminal in the end of 90 the casing at the opposite end of the fuse.

2. A renewable electric fuse, comprising a tubular casing of insulating material having a reduced end and diametrically arranged notches therein, a ferrule fixed on 95 said reduced end and provided with ears projecting inwardly through the said notches, screws fixed in the ends of said ears and projecting beyond the end of the casing, terminal blades for supporting a 100 fuse element in said casing, one of said blades having a cross-bar projecting from opposite sides thereof and having screws fixed therein and adapted to project beyond the end of the casing, and the other of said 105 blades having a cross-bar projecting from opposite sides thereof and provided with openings adapted to engage the screws fixed in the ears on said ferrule, end caps fitted upon the ends of the casing and provided 110 with openings through which the terminal blades and the ends of said screws pass, and nuts adapted to be fitted upon said screws for locking the parts in place.

In testimony whereof, we have hereunto 115 set our hands this 13th day of August 1918, at Pittsburgh, Pa.

FRANK C. LA MAR.
PETER J. HOPKINS.
